(57) **CLAIM**

The ornamental design for a tub with apron, as shown and described.

DESCRIPTION

In a preferred embodiment, the nature of this product is as a tub with apron in the form of a bathing tub, primary useful for washing the human body, and/or an apron structure therefor.

FIG. 1 is a left, top, front perspective view of a tub with apron according to our new design in the form of an apron; FIG. 2 is a top plan view thereof;

FIG. 3 is a left side elevation view thereof;

FIG. 4 is a right side elevation view thereof;

FIG. 5 is a rear elevation view thereof;

FIG. 6 is a bottom plan view thereof; and,

FIG. 7 is a front elevation view thereof.

The broken line showing of portions of the tub are for illustrative purposes and form no part of the claimed design.
